GOLF PUTTING COURSE UNIT

Harry Ganger, 168 S. Maryland Ave., Atlantic City, N.J.

Filed Nov. 12, 1964, Ser. No. 82,560

Term of patent 3½ years

(Cl. D34—5)

FIG. 3

FIG. 4

FIG. 5

FIG. 6

FIGURE 1 is a top perspective view of a golf putting course unit showing my new design.

FIGURE 2 is a top plan view of the golf putting course unit of FIGURE 1;

FIGURE 3 is an end elevational view of my golf putting course unit as seen from the right-hand end of FIGURE 2;

FIGURE 4 is an end elevational view of my golf putting course unit as seen from the left-hand end of FIGURE 2;

FIGURE 5 is an enlarged partial top plan view of my golf putting course unit, showing approximately the left half as seen in FIGURE 2, and illustrating the course in greater detail; and

FIGURE 6 is a partial side elevational view as taken from the right-hand side of FIGURE 5.

I claim:
The ornamental design for a golf putting course unit, as shown.
